(57) **CLAIM**

The ornamental design for the sensor for fingerprint detectors, as shown and described.

DESCRIPTION

FIG. 1 is a perspective view of a sensor for fingerprint detectors showing the new design.

FIG. 2 is a top plan view thereof.

FIG. 3 is a left side elevational view thereof. The right side elevational view is identical to the left side elevational view.

FIG. 4 is a bottom plan view thereof; and,

FIG. 5 is a front elevational view thereof. The rear elevational view is identical to the front elevational view.
